UNITED STATES PATENT OFFICE.

WILLIAM MEYER, OF CHICAGO, ILLINOIS.

THERAPEUTIC APPARATUS.

Application filed December 18, 1918. Serial No. 267,234.

To all whom it may concern:

Be it known that I, WILLIAM MEYER, a citizen of the United States, residing at Chicago, in the county of Cook and State of Illinois, have invented a certain new and useful Improvement in Therapeutic Apparatus, of which the following is a full, clear, concise, and exact description, reference being had to the accompanying drawings, forming a part of this specification.

My invention relates to therapeutic apparatus and more particularly to a table for use in taking X-ray photographs of the body and for administering electric treatment.

In taking X-ray photographs or radiographs, as they are often termed, it is necessary to hold the sensitized plate in a fixed position so that the proper degree and location of exposure will be obtained. Where the plate is attached to the patient, movement of the patient will take the plate out of the proper position and will prevent the proper degree and proper location of the exposure. This is particularly true in diagnosing the condition of the frontal sinuses which has heretofore been an extremely difficult matter and also in the fluoroscopic examination of the neck and other X-ray work about the head, which has heretofore been extremely inconvenient.

I have found that the only dependable method of making exposures is to have the patient rest upon a support which also supports the photographic plate. Thus the patient being properly supported, the chances of movement are much lessened, although a slight movement would not destroy the adjustment of the plate with respect to the X-ray tube.

My invention aims to provide a suitable table, comparatively light in weight, which is so constructed that it may be readily adjusted for either electrical treatments, fluoroscopic work or making radiographs of any part of the anatomy.

In accordance with the teachings of my invention I provide a suitable support in the form of a table, which is provided with an adjustable portion for holding the patient in any desired angular position, this adjustable portion at the same time serving to hold the photographic plate in a number of positions to provide the maximum utility for X-ray purposes.

I have further provided an adjustable plate holding head rest adjacent the opposite

end of the table for holding the head of the patient at any desired angular position, either above or below the plane of the table top. This feature is particularly adapted for making radiographs of the frontal sinuses, fluoroscopic examination of the neck, for dental radiographs, or other work about the head where difficult fixed angular positions are often necessary in order that clear and sharp detail will be secured.

I have further provided for mounting the tube upon a standard adjustable longitudinally along the table, means being provided for securely locking the standard in any desired position therealong. The tube carrier is adapted to be swung about the standard, away from the table, thereby giving all the facilities of a separate tube stand.

The top itself of my improved table is adapted for supporting photographic plates when it is desired to make an exposure of the central part of the anatomy, suitable means being provided for aligning the photographic plates properly on the table top in such instances. Thus upon placing the patient properly upon the table, exposures of the upper, lower or central parts of the anatomy can be taken without disturbing the patient and with relatively little difficulty.

In order that those skilled in the art may be fully acquainted with the nature and scope of my invention, I shall describe a specific embodiment of the invention in connection with the accompanying drawings which form a part of the present specification.

Figure 1 is a side elevational view of my improved table, illustrating the manner in which the plate holding adjustable portions thereof are available for various positions of the patient;

Figure 2 is a plan view of the same;

Figure 3 is a longitudinal sectional view taken substantially on the line 3—3 of Figure 2;

Figure 4 is an enlarged vertical sectional view taken on the line 4—4 of Figure 3;

Figure 5 is an enlarged vertical sectional view taken on the line 5—5 of Figure 3;

Figure 6 is an enlarged fragmentary vertical sectional view taken on the line 6—6 of Figure 1; and

Figure 7 is a plan view of one of the plate holders.

The embodiment of my invention illus-

trated in the drawings comprises the four corner posts 1, 2, 3 and 4. These posts or legs are secured together by suitable side pieces 5 and 6 and suitable end pieces 7 and 8, 5 to form a rectangular frame. An additional side piece or side rail 9 extends between the posts or legs 3 and 4, the opposite ends of this side piece being secured to the posts 3 and 4, respectively, adjacent their 10 lower ends as shown in Figure 1. The rail 9, together with the side piece 6, is adapted for supporting and guiding the tube standard longitudinally along the table, as will be hereinafter described.

15 The side pieces 5 and 6 have suitable transverse braces 10, 11 and 12 extending between them, as shown in Figures 3, 4 and 5, the opposite ends of these braces being suitably secured to the side pieces 5 and 6, as by means 20 of tenon joints or otherwise. The transversely extending braces 10, 11 and 12 are employed in connection with the adjustable plate holding mechanism, as will be described later. A longitudinal brace 13 shown 25 in Figures 3 and 4 is secured to the transverse brace 11 adjacent its lower edge and to the end piece 8. This longitudinal brace 13 is employed in connection with the adjustment of the plate holding head rest mechanism, as will be described. The sides 5 and 6 and the ends 7 and 8 may be further braced in any preferred manner, such as by the corner braces 14 shown in Figure 2 whereby the corner posts 1, 2, 3 and 4 are removably secured to the sides and ends of the table.

30 A suitable top 15 extends over and covers that portion of the frame bounded by the bracing strip 10, the end piece 8 and the side pieces 5 and 6. This top is preferably finished in natural wood, as is the rest of the table, although it is to be understood that it could be covered with suitable fabric or the like, if so desired. An opening of a size sufficient for the reception of the hinged plate 35 holding head rest 16 is provided in the top 15 adjacent the right end thereof (Figure 1).

The inner edge of the plate holding head rest 16 is hinged to the outer side of the transverse brace 11 so that it may be raised 40 or lowered about these hinges into any desired position as shown in Figure 3. The plate holding head rest 16 comprises a frame 17 which is grooved as shown at 18 in Figures 3 and 4 for receiving the plate holder 19. The frame 45 17 is provided with a covering 20 of aluminum or other conducting material which will not interfere materially with the passage of X-rays therethrough. The covering 20 is stretched upon the frame 17 so that it will not sag, the opposite edges of this covering being bent down and secured to the opposite edges of the grooved frame 17, as shown in Figure 4. The outer edge of the covering 20 is held securely in place by 50 55 60 65 means of a transverse bar 21, the opposite

ends of which are secured to the frame 17. The transverse bar 21 may be nickelized, if so desired, to give the outer edge of the plate holding head rest 16 a finished appearance. 70 A bracket 22, having a pair of arms extending downwardly therefrom in parallel spaced relation, is secured to the under side of the frame 17. The upper end of a rod 23 is journaled between the downwardly extending arms of the bracket 22. The lower end of the rod 23 passes through a bolt 24 which is carried by the longitudinal brace 13. The opposite threaded end of the bolt 24 is provided with a thumb nut 25 for securely gripping the rod 23 in any desired position, the 80 rod 23 being guided in the bolt 24 upon either upward or downward movement of the plate holding head rest 16. A small lug or stop 26 may be provided adjacent the lower free end of the rod 23 for limiting the upward movement of the head rest 16. In the particular table shown I have provided substantially 45° movement for the head rest 16, that is, it may be inclined to an angle of 22½° above the table top 15 or it may be lowered to an angle of 22½° below the table top. When the head rest 16 is inclined to an angle of substantially 22½° above the table top 15, the stop 26 is adapted to engage the bolt 24 thereby preventing further movement 90 of the head rest 16 upwardly. Then by threading the thumb nut 25 upon the bolt 24, the rod 23 will be securely gripped and the head rest 16 securely held in its uppermost position, it being understood of course that 100 the head rest may be held in the plane of the table top 15 or in any other desired angular position in a like manner. Obviously a greater range of movement could be readily afforded the head rest 16 if it is 105 found desirable.

In order that the head rest 16 may be swung downwardly into various angular positions, I have provided an opening 27 in the end piece 8 as is shown in Figure 3, this opening being of a width substantially equal to the width of the head rest 16. That portion of the upper edge of the end piece 8 which forms the bottom wall of the opening 27 is beveled at substantially 22½° so that the outer edge of the head rest 16 will make parallel engagement therewith when moved to its lowermost position, as shown in dotted lines in Figure 3, thereby forming a suitable stop and support for the head rest when in 110 115 120 its lowermost position.

It will now be apparent that I have provided for properly supporting the head of the patient at any desired angular position in order that radiographs or fluoroscopic examinations may be made of the head at various difficult angles. This facilitates radiography of the frontal sinuses, dental radiography and other X-ray work about the head where exposures of certain 125 130

parts must be avoided in order to give clear and sharp detail which is so desirable.

In order to hold the head of the patient firmly in a fixed position irrespective of the angular position thereof, I have provided a pair of head pads 28 and 29 between which the head of the patient is adapted to be securely held. The head pads 28 and 29 are carried upon the inner ends 10 of the horizontal rods 30 and 31, respectively, these rods extending through the vertical posts 32 and 33, which are suitably mounted upon the upper surface of the head rest 16. The reduced threaded ends of the 15 posts 32 and 33 extend down through the frame 17 of the head rest 16 and engage in suitable nuts 34 whereby these posts are held securely in an upright position. The rods 30 and 31 are slidably mounted in the 20 upright posts 32 and 33 whereby the distance between the pads 28 and 29 may be either increased or diminished. Suitable set screws 35 threading into the upper ends 25 of the posts 32 and 33 are adapted to engage the rods 30 and 31 to securely retain the same in any desired position.

In diagnosing the conditions of the frontal sinuses it is often necessary to place the sensitive plate adjacent the forehead in order to make a record through the long 30 axis of the head. In such instances the patient is placed face down upon the table in such position that the forehead of the patient will bear upon the covering 20 of 35 the head rest 16, the center of the patient's head registering substantially with the point of intersection of the lines 36 and 37 provided on the covering 20. The head rest 16 with the patient's head held firmly 40 in place thereon is then moved either upwardly or downwardly into the desired angular position. A sensitive plate is inserted in the plate holder 19, X-ray tube 38 positioned over the back of the patient's 45 head, as will be described later, and the exposure made.

An anteroposterior radiograph of the neck is made with the patient lying face up on the table, (the head rest 16 being 50 adjusted to give the desired exposure) with the sensitive plate under the back of the neck and the tube 38 arranged vertically over the cricoid cartilage.

The adjustable head rest 16 further facilitates 55 fluoroscopic examination of the neck which has heretofore been extremely inconvenient.

The adjustable portion provided adjacent the opposite end of the table comprises a crossbar 39 lying adjacent the transverse brace 10 and carrying an open frame member 40. The open frame member 40 is connected by means of the hinges 42 to the upper edge of the side piece 6. A rod 43 is 65 pivotally mounted by means of a bracket

45 upon the lower edge of the crossbar 44 carried by the open frame 40. The lower end of the rod 43 passes through a bolt 46 carried by the transverse brace 12, which bolt is provided with a thumb nut 47 for gripping the rod 43 in any desired position. The crossbar 44 which extends longitudinally across the open frame 40 carries a similar adjusting bolt 48 for gripping a rod 49 which is pivotally mounted at its 70 opposite end upon a crossbar 50 by means of a bracket 51. The crossbar 50 extends transversely across the under side of the hinged top portion 52. The inner edge of the top 52 is hinged at 53 to the crossbar 80 39 carried by the open frame 40. Thus the top 52 may be swung into any desired angular position relative to the open frame 40 as shown in Figures 1, 2 and 3.

The top portion 52 comprises a frame 85 which is grooved as shown at 53 in Figures 1 and 5 for receiving the plate holder 54 shown in Figure 7. This frame is provided with a covering 55 of aluminum or other conducting material which will not 90 interfere with the passage of X-rays therethrough. The covering 55 is stretched upon the frame so that it will not sag, the opposite edges of this covering being bent down and secured to the opposite edges of 95 the grooved frame as shown in Figure 5.

In use the open frame member 40 and the top portion 52 are adjustable into any convenient position for receiving the patient and making proper X-ray exposures. I 100 have found that a flat table is very uncomfortable for most patients and I prefer to raise the adjustable portion slightly so as to remove this inconvenience. When radiographs of the shoulders or thorax are to be made the patient is placed upon the table in such position that the shoulders will rest upon the covering 55 of the adjustable portion 52 which is then moved up or down in order to secure the proper exposure. A 105 sensitive plate is then inserted in the plate holder 54, the plate being securely held in position in this plate holder by means of the four adjustable strips shown in Figure 7, the X-ray tube 38 moved into position 110 thereabove and the exposure made.

If a radiograph of the groin or of the lower extremities is desired, the sensitive plate is simply placed under the patient and upon the top 15 of the table, being suitably aligned upon the top of the table by means of the parallel line 56 provided thereon as shown in Figure 2.

Where a radiograph of the abdomen is to be taken the open frame 40 is raised as shown 125 in Figures 1 and 2 to an angle of substantially 90° to the top 15 of the table, the top portion 52 is then swung about the hinges 53 to an angle of substantially 90° to the frame 40. It will now be apparent 130

that the patient may stand to one side of the table with the abdomen adjacent the aluminum covering of the top portion 52, the X-ray tube 38 being then placed in back of the patient, that is, substantially in the position shown in Figure 1 and the rays directed through the body as may be required. This adjustment of the open frame 40 and the top portion 52 may be also used in making radiographs of the shoulders or thorax, the patient assuming a sitting posture in such instances.

The tube standard 58 shown in Figure 1 is supported and guided longitudinally along one side of the table by means of suitable guiding rods 59 and 60 provided along the bottom edge of the side piece 6 and along the top of the rail 9, respectively. Guiding members 61 bearing rollers 62 which engage about the peripheries of the rods 59 and 60 are clamped in proper position upon the tubular standard 58 by means of suitable bolts 63. The tube supporting frame 64 and consequently the tube 38 are adjustable vertically and angularly about the tubular standard 58 and in addition may be tilted on the standard in order to direct the X-rays at the proper angle and in correct proximity to the object or patient. This universal adjustability of the X-ray tube 38 is fully described in Patent No. 1,414,658, dated May 2, 1922.

The upper guiding member 61 is provided with a pair of inwardly extending arms 66 as shown in Figure 6. The U-shaped clamping member 67 is journaled between these arms by means of a suitable bolt. The upwardly extending arms 68 of the U-shaped clamping member 67 engage the inner and outer edges respectively of the guiding rail 59. A clamping bolt 69 extends through the enlarged portion 70 of the guiding member 61, through the upwardly extending arms 68 of the U-shaped clamping member 67. The inner reduced threaded portion of the bolt 69 provides an annular shoulder which engages the outer surface of the guiding member 61 thereby preventing inward movement of the bolt 69. Outward movement of this clamping bolt may be prevented by means of a suitable pin 71 thereby maintaining the bolt 69 in a fixed position. Thus, upon revolving the bolt 69, the upwardly extending arms 68 of the U-shaped clamping member 67 will be securely clamped into engagement with the outer and inner edges respectively of the guiding rail 59, thereby effectively locking the tube standard 58 against longitudinal movement along the table.

It will be apparent that upon raising the tube supporting frame 64 to a point adjacent the top of the tubular standard 58, that this increased weight might have a tendency to tip the table over on its side. To counter-

act any such tendency I have provided a counterweight 72 which may be bolted or otherwise suitably secured to the inner side of the side piece 5, as shown in Figure 3.

The four corner posts or legs 1, 2, 3 and 4 of my improved table are provided with anti-friction rollers or casters 73 in order that the entire table may be readily moved into any desired position. These legs are further provided with suitable stops 74 which comprise a stop member, means for holding the stop member in engagement with the floor and suitable means whereby the stop member may be released as well understood by those skilled in the art. Thus the table may be moved into any desired position and effectively locked against accidental movement by means of the stop 74.

While I have described my invention with reference to the details of a particular embodiment, it is to be understood that I do not intend thereby to limit my invention to the proportions or dimensions or precise construction shown and described, but intend that all such modifications as will suggest themselves to one skilled in the art, be considered as coming within the spirit and scope of my invention.

What I claim is:

1. In an X-ray table, a top portion having a notch in one end, a head-rest pivoted about the inner edge of said notch for movement above and below the table level, standards rising from the sides of said head rest and positioned to clear the side edges of said notch, cross slides in said standards projecting out laterally past the vertical plane of the edges of said notch, and means forming part of the fixed structure of said table positioned in the path of said head section to prevent bringing said slides against the edges of said notch by downward movement.

2. An X-ray table, having a fixed section of slightly greater length than is necessary to support a human trunk and head, said section having a notch in one end, a tiltable head rest pivoted about the inner edge of said notch, and a tiltable section of full width pivoted to the opposite end of said fixed section, said last mentioned tiltable section being of sufficient length to support a human trunk.

3. An X-ray table, having a fixed section of slightly greater length than is necessary to support a human trunk and head, said section having a notch in one end, a tiltable head rest pivoted about the inner edge of said notch for movement above and below the table level, and a plate holder concealed in said head rest.

4. An X-ray table, having a fixed section of slightly greater length than is necessary to support a human trunk and head, said section having a notch in one end, a tiltable head rest pivoted about the inner edge of

said notch for movement above and below the table level, and head clamps at opposite sides of said head rest arranged to clear the sides of the notch.

5. An X-ray table, having a fixed section of slightly greater length than is necessary to support a human trunk and head, said section having a notch in one end, and a tilttable head rest pivoted about the inner 10 edge of said notch for movement above and below the table level.

6. An X-ray table, having a fixed section of slightly greater length than is necessary to support a human trunk and head, said 15 section having a notch in one end, and a tilttable head rest pivoted about the inner edge of said notch.

7. In an X-ray table, a fixed top portion, a tilttable section of full width at one 20 end of said top portion, said fixed portion having a notch in its opposite end, a head section pivoted about the inner edge of said notch, both tilttable sections having top pieces transparent to X-rays, and plate 25 holders underlying said top pieces.

8. In an X-ray table, a fixed top portion, a tilttable section of full width at one end of said top portion, said fixed portion hav-

ing a notch in its opposite end, a head section pivoted about the inner edge of said 30 notch, and plate holders concealed in both tilttable sections.

9. In an X-ray table, a fixed top portion, a tilttable section of full width at one end of said top portion, said fixed portion having a notch in its opposite end, and a head 35 section pivoted about the inner edge of said notch.

10. In an X-ray table, three sections, the combined length of any two sections being 40 insufficient to support the patient, one end section being long enough to carry the head, and the other end section being longer to carry the head and thorax, and plate holders concealed in said end sections. 45

11. In an X-ray table, three sections having a combined length substantially equal to that of the patient, one end section being long enough to carry the head of the patient, and the other long enough to carry 50 the head and thorax, the center section having a notch receiving the head section.

In witness whereof, I hereunto subscribe my name this 14th day of December, A. D. 1918.

WILLIAM MEYER.
